METHOD OF ANNEALING AND APPARATUS
THEREFORLazenby C. Hamlink, Cleveland Heights, Ohio,
assignor to The Gas Machinery Company,
Cleveland, Ohio, a corporation of Ohio

Application November 23, 1935, Serial No. 51,292

3 Claims. (Cl. 266—5)

My invention relates to improved methods of annealing metal sheets and improved apparatus by which such methods may be worked. The particular objects of the invention are to devise 5 methods of operation and apparatus by which satisfactory continuous annealing may be effected conveniently and with an economy of fuel and at the least loss of time and expenditure of effort in passing through the successive stages of a complete annealing operation and in passing from 10 the annealing of one batch of sheets to the annealing of another batch of sheets.

The annexed drawings and the following description set forth in detail certain steps illustrating the manner of carrying out my new and improved method and certain apparatus by which the method can be worked, such disclosed steps and apparatus constituting, however, but one of the various series of steps by which the method 20 may be worked and but one of the various forms of apparatus in which the principle of the invention may be embodied.

In said annexed drawings:

Figure 1 is a plan view of a pile of metal sheets 25 positioned upon a working base and covered by a so-called inner cover which is partly broken away, the base, cover, and sheets being associated with a working floor provided with certain underground conduits and manholes, and hand covers 30 for the manholes, utilized in the working of my improved methods of annealing;

Figure 2 is a plan view of a base, inner cover, and a pile of sheets covered by a certain heating cover utilized during the annealing operation 35 proper, the flow directions of the combustion air and gases and the products of combustion being indicated by arrows;

Figure 3 is a transverse vertical section of the 40 elements shown in Figure 2, the view being taken in the planes indicated by the lines 3—3, 3'—3', Figure 2;

Figure 4 is a longitudinal vertical section of the 45 elements shown in Figure 2, the view being taken in the plane indicated by the line 4—4, Figure 2;

Figure 5 is a longitudinal vertical section of the 50 elements shown in Figure 2, the view being taken in the plane indicated by the line 5—5, Figure 2;

Figure 6 is a plan of a working base, a pile of sheets and an inner cover thereon associated with a regenerating cover utilized for preheating combustion air, the flow direction of the air being heated being indicated by arrows;

Figure 7 is a transverse vertical section of the

elements shown in Figure 6, the view being taken in the plane indicated by the line 7—7, Figure 6;

Figure 8 is a plan view of a working base, a pile of sheets and an inner cover thereon associated with a preheating cover utilized for giving 5 the sheet pile a preliminary heating by products of combustion derived from a heating operation effected in the structure shown in Figures 2, 3, 4 and 5, the flow movements of the products of combustion into the preheating cover and the 10 waste products out from the preheating cover being indicated by arrows;

Figure 9 is a transverse vertical section of the 15 elements shown in Figure 8, the view being taken in the plane indicated by the line 9—9, Figure 8;

Figure 10 is a longitudinal vertical section of the 20 elements shown in Figure 8, the view being taken in the plane indicated by the line 10—10, Figure 8;

Figure 11 is a plan view, upon a reduced scale, 25 of five units carrying out the entire cycle of my improved method of annealing, the view showing multiple stations, complete in themselves as a whole for effecting the entire cycle of operations, or capable of use, if desirable, with additional 30 stations; at which five stations various annealing and cooling functions can be simultaneously effected upon a plurality of batches of sheet steel, the several batches being heated by the use of a single heating cover utilized at the several stations in rotation. The stations at which the 35 movable heating cover is not being used at any one time are respectively utilized by the aid of other covers to perform certain other operations of the annealing cycle upon other batches. This view also shows the conduits and pipes for the conveyance and transfer during the annealing operation of the fuel and air for combustion, and the products of combustion, and the waste products of combustion. In this view the unit at the 40 left end is shown in use for air cooling a pile of annealed and hot sheets under an inner cover; the next unit is a regenerating one and is preheating air intended for combustion, by the heat derivable from a pile of sheets from which a heating cover has just been removed; the next or middle unit is heating a pile of sheets under a heating cover; the next unit or the one second from the right is preheating a pile of sheets next 45 to be covered by the heating cover of unit 3; and at unit 5 or the right hand unit, a new pile of sheets is in position under an inner cover ready for the annealing treatment;

Figure 12 is a view similar to Figure 11 in 50 which the heating cover of Figure 11 has been 55

5 moved to station 4 from station 3, and the other stations are shown correspondingly advanced to the next stage of their annealing and cooling operations, it being noted that the stages of 10 operation move successively from left to right and are transferred from the extreme right station to the extreme left station after having been performed at the extreme right station; in other words, the cycle of operations is performed in a 15 closed circuit; and

10 Figures 13, 14, and 15 are views similar to Figures 11 and 12 but showing successively further stages of operation at the several stations of the annealing assembly.

15 Referring to the annexed drawings in which the same parts are designated by the same respective numbers in the several views, I provide beneath the surface of a working floor 1 three parallel horizontal underground conduits 2, 3, and 4, all at the same level, of which one outer conduit 2 serves for transfer of products of combustion having effective heat, the other outer conduit 3 serving to transfer to a stack 5 waste products of combustion, and the intermediate conduit 4 serving to transfer preheated air for combustion. On the floor level and between the vertical projections of the outer conduits 2 and 3, I provide a plurality of bases 6 serving as supports for various covers utilized in the annealing operation, and hereinafter fully described, these bases 6 serving as stations at each of which all the different steps of the annealing process are effected in succession. While one step of the annealing process is being carried out at one 30 station, other steps of the annealing process are being carried out simultaneously and respectively at the other stations. In other words, any one batch of sheets is subjected to all operations at one station, i. e. maintained in situ during the 35 entire annealing operation, but while one operation is being effected at one station upon one batch of sheets, other operations are being effected at other stations upon other batches of sheets, so that a plurality of stations at which different 40 operations are being conducted are being utilized simultaneously for a plurality of batches of sheets.

45 By means fully herein described, the covers utilized at the several stations intercommunicate in various ways by means of the underground conduits 2, 3, and 4. Communication between the conduits 2, 3, and 4 and the several covers is effected by manholes 7 which serve as valve casings opening into the conduits 2, 3, and 4, and 50 which are upstanding from these conduits and have open upper ends and also have sand or other sealing reservoirs 8 adjacent their upper ends into which removable hand covers 9 dip and serve as valves for closing off the upper 55 ends of the manholes 7 when desired. The arrangement of these hand covers 9 provides the proper setting for the desired transferring of heated air, products of combustion, and waste gases, and the positioning of the hand covers 9 is varied from time to time according to which 60 stations 6 it is desired to utilize for the several annealing operations.

65 These annealing operations are in sequence as shown in the accompanying drawings and described herein in detail for purposes of illustration, first, the positioning of a fresh batch of sheets upon a base 6 from which a batch of annealed and cooled sheets has just been removed (illustrated at the right hand station in Figure 70 75 11); secondly, the preheating of such batch with

the products of combustion derived from the heating of another batch with combusted fuel (illustrated at the station the second from the right in Figure 11); thirdly, the actual heating (illustrated in the middle station in Figure 11); fourthly, the use of the heat from the annealed cooling batch for heating air to be utilized in combustion (illustrated at the next to the left hand station in Figure 11); and, fifthly, the final cooling in air of the annealed batch (illustrated at the left hand station in Figure 11). For these several operations, except for the actual removal of an annealed and cooled batch from, and the positioning of a fresh batch upon, a base 6, an inner cover 10 is utilized, which is well known 15 to those skilled in the art and which rather closely confines the batch. For three of the operations, special covers are also used; one, a preheating cover 11 used for the unannealed positioned batch being preheated by products of combustion; two, a heating cover 12 used for the heating effected by burning fuel gas with preheated air; and three, a regenerating cover 13 used for preheating air by the heat of a cooling batch, this preheated air being passed to the heating 20 cover for mixture with gas to heat the batch under the heating cover 12 at that time.

25 In Figures 11-15, five successive arrangements of the various covers and the means governing the conduits 2, 3, and 4 are shown, and in all these figures combined, the batch of sheets at any station is being subjected to all the different operations or undergoing all the different conditions of the entire annealing process. In these figures, the right-hand batch 30 14 of sheets can be considered to be undergoing the several annealing operations in proper order from Figure 11 to Figure 15, inclusive. In other words, this right-hand batch 14 in Figure 11 is a fresh pile of sheets ready to be heat-treated; 35 in Figure 12, this batch is being preheated by means of the use of the preheating cover 11 and the proper setting of the transfer means for the products of combustion; in Figure 13, this batch 14 is being heated under the cover 12 by the 40 combustion of fuel gas and heated air, the heated air transfer means being properly set and the gas-supply pipes being opened; in Figure 14, this batch 14 is cooling and the heat derived therefrom is being utilized to heat air 45 furnished by a blower 15, the heated air transferring means being set to transfer the air to the batch being heated; and in Figure 15, this batch 14 is receiving its final cooling in air. It 50 will be noted that in all of the Figures 11, 12, 13, 14, and 15, the batch 14 is enclosed by the inner cover 10. The other batches of sheets shown in Figures 11-15 upon the bases 6 are also 55 undergoing the several operations but each one at any one time a different operation from that to which the batch 14 is subjected, and each one at any one time a different operation from that to which any other batch is subjected. Of course, no one batch shown in Figures 11-15, except batch 14, is shown in all of the Figures 60 65 11-15, because batch 14 is the only batch shown in Figure 11 which has as yet received no treatment, the other batches shown in Figure 11 successively completing their cycle of operations, one by one, from Figure 11 down through Figure 14, and being replaced in rotation by a new batch ready to be heat treated.

70 The bases or stations 6 are formed of insulating material and have upper suitable stock supporting portions 6' and lower outwardly-ex- 75

tended shoulder portions 6² forming supports for the inner covers 10. Upwardly-extended from the shoulder 6² and outwardly-spaced from the stock supporting portion 6¹ are refractory plates 20 forming troughs 21 filled with sand or other suitable sealing material. The inner covers 10 are supported upon their lower edges in these sealing troughs 21. The bases or stations 6 are also formed with upwardly-extended peripheral flanges 6³ spaced from the outer vertical walls of the shoulder portions 6² to form troughs 22 filled with sand or other suitable sealing material. The preheating cover 11, the heating cover 12, and the regenerating cover 13 are formed of refractory insulating material and respectively have downwardly-extended flanges 11', 12', and 13' formed of suitable refractory material and adapted to dip into the troughs 22 when these covers 11, 12, and 13 are in position upon the bases or stations 6.

The regenerator cover 13 is additionally provided with a blower 27 whose discharge pipe communicates with a space 28 formed between the inner cover 10 and the inner wall of the regenerator body 13 and entirely surrounding the top and side of the inner cover 10. The regenerator cover 13 is also formed upon the side thereof opposite the blower 27 with a downwardly-extended conduit portion 29 adapted when the regenerator cover 13 is in position on a base or station 6 to communicate with a manhole 7 on the central underground conduit 4, as clearly shown in Figure 7. Assuming that the stack of sheets within the regenerating cover 13 is one which has just been annealed under a heating cover 12, it is evident that the air furnished by the blower 27 is heated in its passage through the cover 13 around the inner cover 10 and is discharged in this heated condition into the central underground conduit 4 whence it is conducted to the heating cover 12, Figures 11-15.

The heating cover 12 is formed with oppositely-disposed downwardly-extended side conduit portions 30 having downwardly-extended bottom flanges 30' adapted to dip into seals 8 of manholes 7 provided upon the central underground conduit 4, Figure 3. Thus the air heated in the regenerator cover 13 can pass to the burners of the heating cover 12 and this it does at both ends of the heating cover 12 and upon both sides through the medium of longitudinal pipes 31 which communicate at one end with conduits 30 and discharge at the other end into burners 32 intersecting the end walls of the heating cover 12 at different levels, as clearly seen in Figure 5. Also feeding into the burners 32 are pipes 33 adapted to furnish gaseous fuel for combustion with the heated air furnished the burners 32 by the longitudinal pipes 31. The fired mixture enters the heating cover 12 at both ends of the side walls thereof and traverses said side walls repeatedly by any suitably formed tortuous conduit 34, one form of such conduit being shown in the accompanying drawings for purposes of illustration, and being formed by walls 40 inwardly spaced from the main outer side walls of the heating cover 12 in combination with horizontal partitions 41 which are alternately open at opposite ends to form a tortuous conduit for the heating gases from bottom to top of the heating cover 12, as clearly shown in Figure 5. The products of combustion pass into end side flues 35 at the top of the heating cover 12 and adjacent one end thereof whence they are conducted laterally to

a downwardly-extended and centrally located flue 36 at one end of the heating cover 12 which is formed in an outwardly-extended end extension 37 of the heating cover 12. The flue 36 communicates with a manhole 7 and the products of combustion are thus discharged into the side underground conduit 2. The extension 37 has a depending flange 37' adapted to dip into the seals 8 formed on the manholes 7 of the underground conduit 2. It is thus evident from Figures 11-15 that the products of combustion from the annealing operation under the heating cover 12 can be conducted toward the preheating cover 11 and they enter said preheating cover 11 through the medium of an outwardly and downwardly extended conduit 38 formed upon one end of the cover 11 and adapted to communicate with the manholes 7 formed upon the underground conduit 2, the upper end of the passage 39 formed in the conduit 38 communicating with a space 42 provided between the inner cover 10 and the side wall of the preheating cover 11 and entirely surrounding the side walls and top of said cover 10. Upon the end of the preheating cover 11 opposite to that provided with the extension 38 is formed another downwardly-extended conduit member 43 forming a passage 44 communicating at its upper end with the space 42 and adapted to communicate, when the preheating cover 11 is in position upon a base or station 6, with a manhole 7 formed upon the side underground conduit 3. Thus it is evident that the waste products of combustion, discharged from the preheating of a stack of sheets in the cover 11 by the products of combustion derived from the heating cover 12, pass to the stack 5. The extensions 38 and 43 of the preheating cover 11 are formed with depending flanges 38' and 43', respectively, adapted to dip into the seals 8 of the manholes 7 when the preheating cover 11 is in position upon the bases 6.

It will be noted in Figures 11-15 that the conduits 2, 3, and 4 are provided with five identical sets of manholes 7, the manholes 7 in each set for any one conduit being identical with the manholes 7 of any other set for the same conduit. Furthermore, the extensions 30 of the heating cover 12, and the extensions 37 thereof, are arranged to register with the manhole 7 of the conduits 4 and 2, respectively, the extensions 38 and 43 of the preheating cover 11 to register with the manholes 7 of the conduits 2 and 3, respectively, and the extensions 29 of the regenerating cover 13 to register with the right-hand manhole 7 of the conduit 4 in each of the sets of manholes, so that in any of the several arrangements of the covers 11, 12, and 13 respectively shown in Figures 11-15, suitable communication is provided between the several conduits 2, 3, and 4 and the covers 11, 12, and 13, those manholes 7 which should be shut off for any particular arrangement of the covers 11, 12, and 13 being closed by the manhole covers 9.

The several covers 10, 11, 12, and 13 can be provided with any suitable means for positioning, and removing, and transferring the same, the particular cooperating means for this purpose that is formed upon the covers being illustrated by elements 23, 24, 25, and 26 on the inner cover 10, preheating cover 11, heating cover 12, and regenerating cover 13, respectively.

From the foregoing description and the accompanying drawings, it is evident that the necessary control of the flow of air and the

products of combustion and waste products of combustion can be obtained, irrespective of the stations on which the several covers 11, 12, and 13 are placed by removing the hand covers 9 from the manholes 7 where communication is necessary between the underground flues 2, 3, and 4 and the several covers, and at the same time covering the manholes 7 by hand covers 9 where it is necessary to shut off such communication. It is also evident that for any arrangement of the covers 11, 12, and 13, two of the bases 6, of the five bases 6, which are herein shown and described for purposes of illustration, are provided with stacks of sheets and inner covers 10 which are not in communication with the conduits 2, 3, and 4, or with the other covers; for instance, the left-hand base 6 and the right-hand base 6, Figure 11. More than two such idle stations 6 might be provided, or even one idle station 6 might at times be suitable, depending upon the respective timing of the several operations in a whole cycle of operations. For purposes of illustration, I have shown and described two idle stations 6, upon one of which, the right-hand one in Figure 11, it is considered that a fresh pile of sheets is stacked ready for heat treatment; and upon the other of which, the left-hand station 6, Figure 11, it is considered that a pile of annealed sheets, which in partial cooling has given heat to air under the cover 13 in the previous stage of operations, is now being permitted to take its final cooling in air. The timing of the several operations in a whole cycle of operations determines largely how many stations 6 and inner covers 10 are utilized. For instance, if the regenerative operation adequately cools the batch which has been annealed, this batch could be replaced by a fresh batch, while the next operations are being effected, and thus four stations would be utilized, and the annealing process would be continuous. In the event that it were desirable to interrupt the annealing process, three stations might be utilized, and the process interrupted while the cooled batch was being replaced by a fresh batch. However, in Figures 11, 12, 13, 14, and 15, I have assumed, for purposes of illustration, that the annealing process is continuous, and that a final cooling of a treated and preliminarily cooled batch is effected in air after the regenerating cover has been removed therefrom, and while this final cooling is taking place, and the other batches are being respectively preheated, heated and preliminarily cooled, the batch which had finally cooled during the preceding set of operations is being replaced by a fresh batch.

What I claim is:

1. Apparatus for annealing comprising spaced fixed bases, movable covers for said bases adapted respectively for regenerating, annealing, preheating, and cooling operations, and each adapted for mounting upon any of said bases to effect thereon its particular operation, means supplying air to the regenerating cover, burners firing into the annealing cover, and means supplying gas to the burners, a plurality of conduits, one for con-

veying preheated air for combustion from the regenerating cover to said burners, one for conveying preheating products of combustion from the annealing cover to the preheating cover, and one for conveying waste products of combustion away from the preheating cover, said conduits being each provided with a plurality of ports, and removable closures for said ports, the ports being arranged to permit, in combination with their closures, the functioning aforesaid of the respective conduits irrespective of the relative location upon the bases of the several covers. 5

2. Apparatus for annealing comprising spaced fixed bases, movable covers for said bases adapted respectively for regenerating, annealing, preheating, and cooling operations, and each adapted for mounting upon any of said bases to effect thereon its particular operation, means supplying air to the regenerating cover, burners firing into the annealing cover, and means supplying gas to the 20 burners, a plurality of conduits, one for conveying preheated air for combustion from the regenerating cover to said burners, one for conveying preheating products of combustion from the annealing cover to the preheating cover, and one 25 for conveying waste products of combustion away from the preheating cover, said conduits being each provided with a plurality of ports, removable closures for said ports, said conduits including main ducts and auxiliary conduit means associated with the regenerating, annealing, and preheating covers and providing communication through said ports between the interiors of said regenerating and preheating covers and said burners, respectively, and the main ducts, respectively, for the aforesaid conveying functions, 30 respectively, the ports of the several conduits being positioned identically, relatively to all the bases. 35

3. A continuous method of annealing metal articles in multiple batches consisting in providing a system for regenerating, annealing, preheating, and cooling operations, supplying air and gaseous fuel continuously to said system, simultaneously effecting, upon three different batches, preheating, annealing, and cooling operations, respectively, by heating air by a cooling batch, burning gaseous fuel with the heated air to anneal a second batch, using the products of combustion from the annealing operation to preheat 45 a third batch, discharging from the system the waste products of combustion from the preheating operation, and removing from the system a cooled batch and replacing it with a fresh batch; and then, while maintaining the batches in the 50 system in situ, shifting the cycle of operations so as to preheat the fresh batch with products of combustion from an annealing of the batch which had been previously preheated and which now is being annealed by the burning of gaseous fuel 55 with heated air derived from the cooling of the batch which had been previously annealed, and removing from the system a cooled batch and replacing it with a fresh batch, and thus repeatedly shifting the cycle of operations. 60 65

LAZENBY C. HAMLINK.
